UNITED STATES PATENT OFFICE.

HENRY M. MANHEIM, OF NEW YORK, N. Y.

RACK.

No. 873,446.

Specification of Letters Patent.

Patented Dec. 10, 1907.

Application filed June 10, 1907. Serial No. 378,181.

To all whom it may concern:

Be it known that HENRY M. MANHEIM, a citizen of the United States, residing at New York, in the county of New York and State 5 of New York, has invented certain new and useful Improvements in Racks, of which the following is a specification.

This invention has relation to racks adapted to be applied to chairs and similar articles, 10 and it consists in the novel construction and arrangement of its parts, as hereinafter shown and described.

The object of the invention is to provide a rack of simple and cheap construction, 15 which may be easily and readily applied to a chair back, as for instance a theater chair, and which consists of a hollow standard so mounted that it may turn axially, and which is provided with a telescoping 20 arm which may be swung at an angle to the standard and lodged in a recess provided therein, and when so located is adapted to serve as a support for a hat, coat or other article of clothing.

25 Figure 1 is an elevation of the rack with parts in section. Fig. 2 is a perspective view of a standard constituting part of the rack. Fig. 3 is a perspective view of a clip for securing the rack, and Fig. 4 is a perspective view of a ferrule for supporting the rack.

The rack consists of the tubular standard 1, which is reduced in its internal diameter, as at 2, at its upper end, and is provided adjacent its upper end and in one side with a 35 recess 3. The standard 1 is provided at a point intermediate of its ends with a lug 4 outstanding therefrom and struck up from the metal thereof. The lower end of the standard 1 is open and rests upon a ferrule 5, which is provided at one side with a screw 6 adapted to be inserted in the back of the 40 chair. The circular portion 7 of the clip 8 is slipped over the upper end of the standard 1, and the wings 9 of the said clip are secured 45 against the back of the chair by means of screws 10 or their equivalent. The lower edge of the ring 7 rests upon the lug 4, so that the standard 1 may turn axially in the ring 7 and upon the ferrule 5. The arm 11 50 is provided at its lower end with an enlarged head 12, which fits snugly within the standard 1. The arm 11 is inserted in the standard 1 at the lower end thereof. The upper end of the arm 11 is provided with an

enlarged head 13 which is screwed upon the 55 reduced portion 14 of the said arm. The head 13 is of greater diameter than the standard 1. When the rack is not in use the arm 11 is slipped vertically within the standard 1, and the head 13 rests upon the 60 upper end thereof. When the rack is used for supporting articles as described, the arm 11 is slipped longitudinally within the standard 1 until the head 12 comes in contact with the reduced end 2 thereof, when the 65 said arm 11 is permitted to fall laterally and enter the recess 3. When in this position the said arm may be used as a peg or support for an article of clothing. At the same time the said arm may turn with the standard 1; 70 thus it may be moved out of the way and is specially adapted to be used in theaters where the occupants of the seats along the row may desire to gain entrance or have exit 75 therefrom.

The parts are preferably made of metal and are of an ornamental nature, take up small space and are not calculated to interfere with the view of those sitting in the rear.

What is claimed is:—

1. A rack comprising a hollow standard, a ferrule supporting the lower end thereof, said standard being formed with a lug intermediate of its ends and having its upper end reduced and provided with a recess, a clip 85 resting upon said lug, and an arm arranged to slide within the standard and enter the recess thereof and having at its ends enlarged heads adapted to limit the movement of the arm in the standard. 90

2. A rack comprising a hollow standard, a ferrule supporting the lower end thereof, said ferrule having a portion adapted to fit within the end of the standard and a screw adapted to enter a support, said standard having its 95 upper end reduced and provided with a recess, and an arm arranged to slide within the standard and enter the recess thereof and having at its ends enlarged heads adapted to limit the movement of the arm in the stand- 100 ard.

In testimony whereof I have signed my name to this specification in the presence of two subscribing witnesses.

HENRY M. MANHEIM.
